(57) **CLAIM**

The ornamental design for a dish as shown and described.

DESCRIPTION

1. Dish

1.1 : Front

1.2 : Perspective

This design is related to a dish; the shape of the dish is square and the walls rise at an angle of about one hundred degrees with respect to the base; the outer surfaces of the sides of the dish are decorated with vertical incisions extending from the base to the rim; these decorations can be compared to elongated leaves.
